FOUNTAIN PEN

Frank C. Ostheimer, Wichita, Kans.

Application December 11, 1935, Serial No. 53,890

17 Claims. (Cl. 120—47)

This invention relates to fountain pens and particularly to a vacuum filler type pen in which the removable protective cap is employed in creating the vacuum necessary for the filling operation.

The objects of the invention are; first, to provide a novel construction in fountain pens whereby the rubber sac will be eliminated, allowing the entire space inside the barrel to be utilized for ink storage.

Second, to provide means whereby the cap may cooperate with the barrel and associated parts thereof, to create a vacuum to fill the pen with writing fluid to a greater capacity than is possible with the sac type pen.

Third, to provide a vacuum filler type fountain pen in which a vacuum may be created inside the removable cap, when associated with the barrel, the pen dipped into a container of writing fluid, a passage opened between the vacuum chamber and the interior of the barrel or ink reservoir to allow the writing fluid to rise into the reservoir due to the pressure exerted by the atmosphere.

And lastly, to provide a fountain pen of the class described with a minimum number of parts, inexpensive in construction and simple and efficient in operation.

Further objects and advantages of my invention will be apparent by reference to the following description in connection with the accompanying drawing in which I have illustrated several preferred forms of the device.

Fig. 1 is a longitudinal, sectional view through one form of my fountain pen, parts being shown in elevation.

Fig. 2 is a similar view, the passage between the vacuum chamber and the ink reservoir being open.

Fig. 3 is a sectional view on the line 3—3 of Fig. 2.

Fig. 4 is a fragmentary, longitudinal, sectional view through a modified form of my invention prior to the seal expanding operation.

Fig. 5 is a sectional view on the line 5—5 of Fig. 4.

Fig. 6 is a sectional view similar to Fig. 4 showing the position of the parts after the seal expanding operation and prior to the vacuum creating operation.

Fig. 7 is a sectional view on the line 7—7 of Fig. 4.

Fig. 8 is a sectional view similar to Figs. 4 and 6 showing the position of the parts after the vacuum has been created and the passageway

between the vacuum chamber and the ink reservoir has been opened to allow the fluid to rise into the reservoir.

Fig. 9 is a fragmentary, longitudinal, sectional view through a further modified form of pen, preparatory to the engagement of the sealing member by the end of the barrel.

Fig. 10 is a similar view showing the parts in position after the sealing member has been engaged.

Fig. 11 is a similar view showing the position of the parts after the vacuum has been created and the passageway between the vacuum chamber and the ink reservoir has been opened to allow the fluid to rise into the reservoir.

Fig. 12 is a fragmentary, longitudinal, sectional view of the end of the pen shown in Figs. 9 to 11, with a protective plug applied.

Referring now to the drawing by numerals of reference, in the first form of my invention shown in Figs. 1, 2, and 3, the numeral 1 designates a pen barrel having a writing point 2 and filler or feed 3 of usual construction. The end of the pen barrel 1 has a reduced threaded portion 4 with end wall 5 having an offset or eccentrically positioned passage 6 therethrough, opening into the interior of the barrel or ink reservoir 7. In threaded engagement with the reduced portion 4 is a head 8 having an annular skirt portion or flange 9, normally positioned on reduced portion 10 of barrel 1, and which may be provided with knurled, fluted or other gripping surface 9'. 15

A sealing washer 11 is positioned in the female end of head 8 and is adapted to butt against the end wall 5 to seal the offset opening 6 from central passage 12 in head 8. A central opening 13 is provided in washer 11 to correspond with passage 12.

Head 8 has a reduced threaded male tip 14 adapted to engage threaded opening 15 in piston or seal retaining cap 16, a seal member or washer 17 being provided between head 8 and piston cap 16, through which extends a central passage 18.

The periphery of sealing member 17 is adapted to contact the inside surface of protective and vacuum cap 19 when it is applied to the barrel 1, said barrel being of smaller diameter than the inside diameter of the cap 19. An opening 20 is provided in the end of cap 19 for the purpose hereinafter specified.

In filling the pen shown in Figs. 1, 2, and 3, the cap 19 is placed on the end of the barrel 1 as shown in Fig. 1 and, with the head 8 screwed down tightly to close the passage to the reser- 55

voir 7, the cap 19 is forced down onto the barrel to the position shown in dotted lines in Fig. 2, the air in the chamber 21 exhausting through opening 20. With the palm of the hand, indicated at 22, held over the opening 20, the cap 19 may be withdrawn from the barrel until gripping surface 9' of flange 9 is exposed, a vacuum having been created in the chamber 21. Keeping the opening 20 closed and the fingers of the hand firmly holding the head 8 from turning, the point 2 and feed 3 are placed below the surface of the writing fluid in a container and the barrel 1 turned to partly unscrew the head 8 to create space 23, connecting central passage 12 with offset opening 6 and consequently connecting vacuum chamber 21 with ink reservoir 7 to allow the atmospheric pressure to force the writing fluid up into the ink reservoir. The barrel may now be turned to force wall 5 against washer 11 to close opening 6, the pen being filled and ready for service.

In Figs. 4 to 8, both inclusive, I have shown a modified form of pen, very much similar to the first form but having a wider sealing washer 24, the outer periphery of which may be flush with the outside surface of the pen barrel. In the end of head or piston 16 is a transverse groove or slot 25 in which may engage the tongue or rib 26 in the closed end of cap 19, which may be passed over the barrel 1, the air exhausting along the sides between the barrel and the cap.

In filling this modified form of pen, the head 8 is tightly screwed down on barrel 1 and the cap 19 pushed onto the barrel to the position shown in Fig. 6, with the rib 26 engaging slot 25 in cap 16. By firmly grasping the cap 19 and rotating the barrel 1, the piston cap 16 is screwed tightly against sealing washer 24 expanding it as shown to form an airtight seal against the inner surface of the cap 19. The cap and barrel may now be drawn apart until the gripping surface 9' is exposed to view, a vacuum having been created in chamber 21. Dipping the point of the pen into the writing fluid and turning the barrel 45 with respect to the head 8 will cause the ink to flow into the ink reservoir 7 as hereinbefore described. The head may now be turned to seal passage 6 and, removing the cap 19, the retaining cap or piston 16 may be backed off to 50 allow the sealing washer 24 to return to normalcy.

In Figs. 9 to 12, both inclusive, I have shown a further modified form of fountain pen in which the head 27 is provided with a female threaded opening 28 adapted to engage reduced threaded tip 29 of sealing or piston cap 30, having a central opening 31 and a sealing washer 32 held in position by suitable nut 33. The piston cap 30 and its associated parts are normally positioned 60 in the closed end of cap 19 as shown in Fig. 9. With the head 27 screwed down tightly the cap 19 is applied to the barrel and the threaded tip 29 is screwed into opening 28. (See Fig. 10.) The cap 19 and barrel 1 may now be drawn 65 apart and a vacuum created in chamber 21, and after inserting the point of the pen into a source of ink supply, the head 27 may be turned to connect the ink reservoir 7 with the vacuum chamber 21 to fill the pen in the predescribed manner, 70 after which the passage 6 may be closed. A small transverse slot 34 in the sealing cap 30 will allow the air to escape from the chamber 21 when the sealing cap or piston is pushed back into the cap 19 in readiness for future filling 75 operations. To finish off the end of the head

21, a plug 35 may be provided (see Fig. 12) or the head 27 may take the shape as shown at 36 in dotted lines.

In present practice, ordinary fountain pens of the vacuum type must be dipped into the ink container before the vacuum is created and I have found such procedure unsatisfactory because it is difficult to keep the hand steady and any abrupt movement may cause the ink to spill, with attendant inconvenience. With my pen 10 however, the vacuum is created before dipping the pen in the ink and after immersion, a slight turn of the barrel will allow the pen to fill with ink. The barrel may be transparent so that the ink supply in the pen may be easily determined. 15 I have also found that in the ordinary fountain pen, when the ink supply runs low, the heat generated by the user's hand, or body or from any other cause, will expand the air in the ink reservoir, forcing the ink out through the feed, this 20 being a common cause for leaking pens. With my invention, however, the head 8 or 27, whichever the case may be, may be turned to open the reservoir 7 to the atmosphere, relieving any excessive internal pressure. 25

Obviously, changes may be made in form, proportion and details of construction without departing from the spirit of my invention and I do not wish to be limited to the exact construction shown and described herein. 30

From the foregoing it will be apparent that I have provided several novel forms of fountain pens in which the protective cap is utilized for filling purposes and the use of a rubber sac is dispensed with, thereby allowing the entire interior of the barrel to serve as an ink reservoir. The number of parts have been reduced to a minimum without detracting from the desired efficient operating qualities necessary in a commercial product of the nature herein described. 35 It will be seen that there are no metal parts bearing on metal and consequently no parts to wear out rapidly and requiring replacement. The only member to be replaced is the sliding seal member 17 in the first form of the invention, member 24 in the second form and member 32 in the third form, which is normally made of rubber or leather or similar material and which may be replaced easily by the owner of the pen at a negligible cost. 45

What I claim as new and desire to secure by Letters Patent is:—

1. In a fountain pen having a barrel providing an ink reservoir, an elongated cap slidably cooperative with the barrel to form a vacuum in said cap, means operable after the vacuum has been formed in said cap for connecting the ink reservoir with the interior of the cap to allow atmospheric pressure to force writing fluid up into the reservoir. 55

2. In a fountain pen having a barrel providing an ink reservoir, an elongated cap slidably cooperative with the barrel to form a vacuum in said cap, a normally closed passage between the ink reservoir and the interior of the cap, means for opening the passage after the vacuum has been created, to allow atmospheric pressure to force writing fluid up into the reservoir. 65

3. In a fountain pen having a barrel providing an ink reservoir, an elongated cap slidably cooperative with the barrel to form a vacuum in said cap, means operable after the vacuum has been formed in the cap for connecting the ink reservoir with the interior of the cap to allow atmospheric pressure to force writing fluid up 70

into the reservoir, said means comprising a head rotatably carried on the barrel and having a passage therethrough opening into the interior of the cap, a second passage through the end of the barrel sealed from and offset with respect to the first mentioned passage and communicable therewith upon rotation of the head with respect to the barrel.

4. In a fountain pen having a barrel providing an ink reservoir, an elongated cap slidably cooperative with the barrel to form a vacuum in said cap, means for connecting the ink reservoir with the interior of the cap to allow atmospheric pressure to force writing fluid up into the reservoir, said means comprising a head rotatably carried on the barrel and having a passage therethrough opening into the interior of the cap, a second passage through the end of the barrel sealed from and offset with respect to the first mentioned passage and communicable therewith upon rotation of the head with respect to the barrel, said head having an elongated skirt portion sleeved on the barrel, said skirt portion being exposable only after the vacuum has been formed in said cap.

5. In a fountain pen having a barrel providing an ink reservoir, a sealing means cooperative with the barrel, an elongated cap slidably cooperative with the sealing means to form a vacuum in said cap, means operable after the vacuum has been formed in said cap for connecting the ink reservoir with the interior of the cap to allow atmospheric pressure to force writing fluid up into the reservoir.

35 6. In a fountain pen having a barrel providing an ink reservoir, a sealing means cooperative with the barrel, an elongated cap slidably cooperative with the sealing means to form a vacuum in said cap, a normally closed passage between the ink reservoir and the interior of the cap and through the sealing means, means for opening the passage after the vacuum has been created to allow atmospheric pressure to force writing fluid up into the reservoir.

45 7. In a fountain pen having a barrel providing an ink reservoir, a sealing means cooperative with the barrel and having a passage therethrough opening into the interior of the cap, an elongated cap slidably cooperative with the sealing means to form a vacuum in said cap, means operable after the vacuum has been formed in said cap for connecting the ink reservoir with the interior of the cap to allow atmospheric pressure to force writing fluid up into the reservoir, said means comprising a head rotatably carried on the barrel and having a passage therethrough communicable with the passage in the sealing member, a second passage through the end of the barrel sealed from and offset with respect to the first mentioned passage and communicable therewith upon rotation of the head with respect to the barrel.

60 8. In a fountain pen having a barrel providing an ink reservoir, a sealing means cooperative with the barrel and having a passage therethrough opening into the interior of the cap, an elongated cap slidably cooperative with the sealing means to form a vacuum in said cap, means for connecting the ink reservoir with the interior of the cap to allow atmospheric pressure to force writing fluid up into the reservoir, said means comprising a head rotatably carried on the barrel and having a passage therethrough communicable with the passage in the sealing member, a second passage through the end of the

the barrel sealed from and offset with respect to the first mentioned passage and communicable therewith upon rotation of the head with respect to the barrel, said head having an elongated skirt portion sleeved on the barrel, said skirt portion being exposable only after the vacuum has been formed in said cap. 5

9. In a fountain pen having a barrel providing an ink reservoir, a sealing means cooperative with the barrel and having a passage therethrough opening into the interior of the cap, an elongated cap slidably cooperative with the sealing means to form a vacuum in said cap, means for connecting the ink reservoir with the interior of the cap to allow atmospheric pressure to force writing fluid up into the reservoir, said means comprising a head rotatably carried on the barrel and having a passage therethrough communicable with the passage in the sealing member, a second passage through the end of the barrel sealed from and offset with respect to the first mentioned passage and communicable therewith upon rotation of the head with respect to the barrel, said head being operable only after the cap has been retracted on the barrel to expose 20 the head and to create the vacuum. 25

10. In a fountain pen having a barrel providing an ink reservoir, an elongated cap slidably cooperative with the barrel to form a vacuum in said cap, means for connecting the ink reservoir with the interior of the cap to allow atmospheric pressure to force writing fluid up into the reservoir, said means comprising a head rotatably carried on the barrel and having a passage therethrough opening into the interior of the cap, a second passage through the end of the barrel sealed from and offset with respect to the first mentioned passage and communicable therewith upon rotation of the head with respect to the barrel, said head being operable only after the cap has been retracted on the barrel to expose 30 the head and to create the vacuum. 35

11. In a fountain pen having a barrel providing an ink reservoir, an elongated cap slidably cooperative with the barrel to form a vacuum in said cap, means for connecting the ink reservoir with the interior of the cap to allow atmospheric pressure to force writing fluid up into the reservoir, said means being operable only after the cap has been retracted on the barrel to create the 40 45 vacuum. 50

12. In a fountain pen having a barrel providing an ink reservoir, a sealing means cooperative with the barrel, an elongated cap slidably cooperative with the sealing means to form a vacuum in said cap, means for connecting the ink reservoir with the interior of the cap to allow atmospheric pressure to force writing fluid up into the reservoir, said last named means being operable only after the cap has been retracted 55 60 on the barrel to create the vacuum.

13. In a fountain pen having a barrel providing an ink reservoir, a sealing means cooperative with the barrel, an elongated cap slidably cooperative with the sealing means to form a vacuum in said cap, an air escape opening in the normally closed end of the cap to permit the barrel to easily engage the cap, said opening being obstructed during the vacuum creating operation, means operable after the vacuum has been formed in said cap 65 70 for connecting the ink reservoir with the interior of the cap to allow atmospheric pressure to force writing fluid up into the reservoir.

14. In a fountain pen having a barrel providing an ink reservoir, an expansible sealing means co- 75

operative with and normally flush with the barrel, an elongated cap slidably cooperative with the sealing means after the same is expanded to form a vacuum in said cap, means for connecting the ink reservoir with the interior of the cap to allow atmospheric pressure to force writing fluid up into the reservoir.

15. In a fountain pen having a barrel providing an ink reservoir, a sealing means cooperative with the cap and normally flush with the barrel, an elongated cap slidably cooperative with the sealing means to form a vacuum in said cap, means for connecting the ink reservoir with the interior of the cap to allow atmospheric pressure to force writing fluid up into the reservoir, means for expanding the sealing means into peripheral sealing engagement with the interior of the cap.

16. In a fountain pen having a barrel providing an ink reservoir, a sealing means cooperative with the cap and normally flush with the barrel, an elongated

cap slidably cooperative with the sealing means to form a vacuum in said cap, means for connecting the ink reservoir with the interior of the cap to allow atmospheric pressure to force writing fluid up into the reservoir, means on the cap adapted to engage the sealing means to expand same into peripheral sealing engagement with the interior of the cap.

17. In a fountain pen having a barrel providing an ink reservoir, an elongated cap slidably cooperative with the barrel, a slidable seal normally positioned in the closed end of the cap, means for connecting the barrel to the seal to create a vacuum in the cap when the barrel is retracted therefrom and means operable after the vacuum has been created in said cap for connecting the ink reservoir with the interior of the cap to allow atmospheric pressure to force writing fluid up into the reservoir.

FRANK C. OSTHEIMER. 20
